UNITED STATES PATENT OFFICE.

HERMAN KANEL, OF NORTH CANTON, OHIO.

DESIGN FOR A SIGNBOARD OR SIMILAR ARTICLE.

Application filed October 27, 1927. Serial No. 23,900. Term of patent 7 years.

To all whom it may concern:

Be it known that I, HERMAN KANEL, a citizen of the United States, residing at North Canton, in the county of Stark and State of Ohio, have invented a new, original, and ornamental Design for a Signboard or Similar Article, of which the following is a specification, reference being had to the accompanying drawing, forming part thereof.

In the drawing:

Fig. 1 is a perspective view of the signboard, or similar article, showing my new design, and

Fig. 2 is a side view thereof.

I claim:

The ornamental design for a signboard, or similar article as shown.

HERMAN KANEL.
